United States Patent Office

Des. 182,603
Patented Apr. 22, 1958

182,603

CHART RACK OR THE LIKE

Alice Liechti and Jack Chappell, San Mateo County,
Calif.

Application July 30, 1957, Serial No. 47,155

Term of patent 14 years

(Cl. D33—3)

Figure 1 is a perspective view of the chart rack showing our new design, in operative position;

Figure 2 is a front elevation thereof;

Figure 3 is a top plan view thereof; and
Figure 4 is an end elevational view.

We claim:

The ornamental design for a chart rack or the like, as shown.
